UNITED STATES PATENT OFFICE

EDWARD E. BARTLETT, OF SAPULPA, OKLAHOMA

DESIGN FOR A TUMBLER

Application filed April 16, 1930. Serial No. 35,269. Term of patent 14 years.

To all whom it may concern:

Be it known that I, EDWARD E. BARTLETT, a citizen of the United States, residing at Sapulpa, Creek County, Oklahoma, have invented a new, original, and ornamental Design for Tumblers, of which the following is a specification, reference being had to the accompanying drawing, forming part thereof.

The figure is a perspective view of a tumbler showing my new design.

I claim:

The ornamental design for a tumbler, substantially as shown.

In testimony whereof I have hereunto set my hand.

EDWARD E. BARTLETT.
